UNITED STATES PATENT OFFICE.

FRITZ AXELSON, OF DENVER, COLORADO.

ROPE-SPlicing SHACKLE.

1,095,446.

Specification of Letters Patent.

Patented May 5, 1914.

Application filed December 24, 1912. Serial No. 738,400.

To all whom it may concern:

Be it known that I, FRITZ AXELSON, a citizen of the United States, residing in the city and county of Denver and State of Colorado, have invented certain new and useful Improvements in Rope-Splicing Shackles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in devices adapted for use in connecting the short end of a rope with the body of the latter where a loop is formed. Heretofore, so far as I am aware this has been accomplished by splicing the rope or interweaving the strands or threads of the short end with those of the body of the rope; or by winding the end and body of the rope with twine, wire, or other material for the purpose of securely connecting the short end of the rope with the body thereof to form the loop or eye for the purpose of connecting the rope by means of a snap hook, S-hook, or other device, when the rope is employed for hoisting purposes or in any other suitable manner.

My object is to provide a device which shall be exceedingly simple in construction and at the same time adapted to effectively perform the function of connecting the short end of the rope with the body thereof in forming the loop, the device being of such shape that the loop may be formed with great facility. Furthermore, where my improved shackle is employed the short end of the rope may be disconnected from the body of the rope when it is desired to loosen the rope from the article to which it is attached, hence the superiority of a device of this character for performing the splicing function.

Generally speaking, my improved shackle consists of a piece of metal having hooks formed on its opposite extremities and approximately in line with each other in a longitudinal direction or lengthwise of the shackle, the two hooks being formed at right angles to each other and connected by a shank diagonally arranged with reference to the axis of the shackle or of the rope with which the shackle is connected. One of the hooks of the shackle engages the loop of the

rope on the inside and constitutes a wearing part which is engaged by the hook connected with the end of the rope, thus relieving the rope from the direct wear incident to the engagement of the hook directly with the loop of the rope.

Having briefly outlined my improved construction I will proceed to describe the same in detail, reference being made to the accompanying drawing in which is illustrated an embodiment thereof.

In this drawing, Figure 1, is a detail view of my improved rope splicing shackle shown in connection with a snap hook, the rope to which the shackle is adapted to be applied being indicated by dotted lines. Fig. 2, is a view taken at right angles to Fig. 1, or a view looking in the direction of arrow 2, Fig. 1, the rope, however, being shown in full lines. Fig. 3, is a view looking in the opposite direction from that shown in Fig. 2, or a view looking in the direction of arrow 3, Fig. 1, with the rope shown in full lines.

The same reference characters indicate the same parts in all the views.

Let the numeral 5 designate my improved shackle considered in its entirety. The body or shank 6, of the shackle extends in the general direction of the line of the rope 7 to which the shackle is adapted to be applied. This shank or body 6, however, extends diagonally to the direction of the axis of the rope 7, or the longitudinal axis of the loop 8, which is formed and maintained through the instrumentality of my improved shackle. At one extremity of the shank 6, is formed a hook 9, which conforms approximately to the curve of the inside of the loop 8, the exterior surface of the hook being hollowed out or transversely concaved as shown at 10, to conform to the curve of the rope, while the hook is bent to conform to the inside curve of the loop as heretofore stated. The opposite extremity of the shank 100 or body 6, of the shackle is provided with a hook 12, which is bent to pass around the adjacent part of the short end 13, of the rope on the outside, thus forming a seat in which the short end of the rope fits closely.

The free extremity 14, of this hook 12, extends transversely somewhat beyond the short end of the rope whereby a seat is also formed for the body of the rope which occupies a position in engagement with the short end of the rope but beyond the latter in the direction of the mouth, between the

free end of the hook and the point 15, of the shank thereof.

As illustrated in the drawing the shackle is shown connected with the end 16, of a snap hook 17, of ordinary construction, the hook member 18, of the snap hook having a swiveled connection 19, with the end 16, in the usual manner.

In applying my improved shackle to a 10 rope for the purpose of forming a loop 8, therein, where a snap hook of the character illustrated is to be employed in connection with the shackle, the hook 9, of the shackle is passed through the eye 16, of the snap hook, after which the free end 13, of the rope is passed through the eye of the snap hook between the hook 9, of the shackle, and the swivel 19, of the snap hook. This free end of the rope is drawn through far 20 enough to permit of its being seated tightly in the hook 12, while at the same time it extends a short distance beyond the last named hook in order that it may be retained securely in place. Before placing the short 25 member of the rope within the grasp of the hook 12, the body of the rope or the longer portion thereof, adjacent the free end, is drawn forwardly from the shank of the shackle, between the two hooks thereof, this 30 body portion being drawn toward the operator approximately parallel with the direction in which the free extremity 14, of the hook 12, of the shackle extends. This act forms a sort of a kink in the longer portion 35 of the rope whereby the latter extends part way around the shank of the shackle, and in engagement therewith. The operator then

holds the longer portion of the rope in the aforesaid position and forces the short end or portion of the rope adjacent the free extremity of the latter, into the bottom of the hook 12, after which the body or longer portion of the rope is drawn in the general direction of the free extremity thereof, and as power is applied thereto, in the direction of 45 its length, it is caused to press tightly upon the short end of the rope, while the latter is securely retained within the hook 12.

Having thus described my invention, what I claim is:

1. A shackle comprising a shank, a longitudinally arranged hook at one extremity adapted to be inserted into the loop of an article to be secured, said hook having in its outer side a groove for the reception of 55 a rope, said shank having at its opposite extremity a transversely arranged hook adapted to receive first the short end and then the long end of the rope, whereby tension upon the long end binds the two together with 60 increased force.

2. In a device of the class described, a shank having a hook at one extremity and a groove in the outer side of said hook, and means at the opposite extremity of the shank 65 for removably retaining both the long and short ends of a rope passed around the groove in the said hook.

In testimony whereof I affix my signature in presence of two witnesses.

FRITZ AXELSON.
